United States Patent Office

THOMAS HOLMES, OF BRISTOL, RHODE ISLAND.

Letters Patent No. 65,811, dated June 18, 1867.

IMPROVEMENT IN WATER-ELEVATORS.

The Schedule referred to in these Letters Patent and making part of the same.

TO ALL WHOM IT MAY CONCERN:

Be it known that I, THOMAS HOLMES, of Bristol, in the county of Bristol, in the State of Rhode Island, have invented a new and useful Improvement in Well-Curbs and their Mechanism for Drawing Water; and I do hereby declare that the following is a full and correct description thereof, reference being had to the accompanying drawing, forming part of this specification, and to the letters of reference marked thereon.

The drawing shows a side view partly in perspective, with a portion of the side of the curve removed to show the arrangement of a part of the mechanism.

The construction is as follows: A is the body of the curb, which may be of the usual form. A drum, B, is placed across the curb, having its pivots resting in bearings *a* in the sides of the same. A rim, C, having cogs on its inner surface, is secured on the end of the drum B, and a smaller wheel or pinion, D, with cogs, is fastened to a short crank-shaft, S, which shaft is placed in a bearing, L, so as to bring the cogs of the pinion D to mesh into those on the rim C, so as to drive it when the crank R, upon the outer end of the shaft, is turned. G is a lever placed across the side of the curb under the rim C, and is hinged to the back side of the curb. This lever forms a brake to press against the outside of the rim C, to regulate the descent of the bucket into the well. A ratchet-wheel, E, is fastened to the crank-shaft beside the pinion, into which the pawl F is arranged to fall; to hold the drum from turning when required. This pawl F is connected to the brake-lever by the bar *l*, so that when it is desired to let the bucket down, by raising the lever G, to bring the brake to bear to control the speed of its descent, the pawl is raised out of the ratchet-wheel by the bar *l*, so as to allow the drum to turn.

Some of the advantages of this arrangement are that by the use of the gear-wheels a larger drum than usual can be used, so that where a well is deep the drum will have more room for a rope of great length without the necessity of winding one coil or layer over another, which wears the rope out fast, or carrying the bucket too far to one side of the spout to be caught and tipped when drawn up. Also by using gear-wheels of this description the crank and drum will revolve in the same direction, which is a great convenience. The facility with which the brake-lever and pawl can be operated by one motion make a very handy arrangement, which, in an article in such continual use, amounts to a great deal in the course of time. A cover, P, to the curb is shown in the drawing, also a plan for tipping and emptying the bucket; but as these are not claimed as new, they will only be mentioned.

Having thus described my improvement, what I claim as my invention, and desire to secure by Letters Patent, is as follows:

I claim the combination of the brake-lever G and pawl F with the gear-wheels D C, when arranged substantially as described and for the purpose set forth.

THOMAS HOLMES.
